[57] CLAIM

The ornamental design for a casing for electrical equipment, substantially as shown and described.

DESCRIPTION

FIG. 1 is a front elevational view of a casing for electrical equipment showing my new design;

FIG. 2 is a side elevational view, the opposite side being a mirror image thereof;

FIG. 3 is a rear elevational view thereof;

FIG. 4 is a top plan view thereof;

FIG. 5 is a perspective view thereof;

FIG. 6 is a front elevational view of a second embodiment of a case for electrical equipment;

FIG. 7 is a side elevational view of FIG. 6 the opposite side being a mirror image thereof;

FIG. 8 is a rear elevational view of FIG. 6;

FIG. 9 is a top plan view of FIG. 6; and

FIG. 10 is a perspective view of FIG. 6.

The undisclosed bottom is flat and unornamented.
